United States Patent Office.

ELAM O. POTTER, OF CHICOOPEE, MASSACHUSETTS.

Letters Patent No. 80,999, dated August 11, 1868.

IMPROVED METHOD OF FORMING STOCKINGS.

The Schedule referred to in these Letters Patent and making part of the same.

TO ALL WHOM IT MAY CONCERN:

Be it known that I, ELAM O. POTTER, of Chicopee, in the county of Hampden, and Commonwealth of Massachusetts, have invented a new and improved Stocking; and I do hereby declare that the following is a full, clear, and exact description thereof, reference being had to the accompanying drawings, making a part of this specification, and to the letters of reference marked thereon, in which—

Figure 1 is a plan view of the knitted fabric, from which the stocking is made, in the condition in which it leaves the knitting-machine, and

Figure 2 is a view of a completed stocking as formed by my method from the part shown in fig. 1.

My invention is designed to be applied to the manufacture of hosiery in large quantities in manufactories of such goods, and enables me to make the same wholly by knitting-machines and sewing-machines, and to dispense with the labor and unevenness of hand-sewing or crocheting the different parts of the leg together, and to form a seam which can hardly be distinguished from the texture of the knitted work, and is as elastic and yielding at the line of joining as at any other part.

The method of forming said stocking is as follows: The part shown in fig. 1, which I will denominate the web, is formed in a knitting-machine, the work being begun at the point *d* of the toe, and knitted, in a conical tubular form, to the line *a c*, thus forming the forward part of the foot. The machine is then adjusted to knit flat work, or the work already done is transferred to a machine which is kept adjusted for flat work, and a flat web, *B A*, is then formed, the width of which will be about one-half the circumference of the tubular part at *a c*. The length of this flat web is somewhat greater than twice the length of the proposed leg above the line *a c*, enough extra length being allowed to give material for the heel of the stocking. The tubular part may be knit plain, and the flat web of ribbed work, so as to produce an elastic leg, or both may be of the same texture, and the web may be of varying width, so as to shape the leg in any desired form. The web is now ready to be cut across at the line *m m*, and transferred to the sewing-machine. The part *A* will then be applied to the remainder of the web, being turned down, so that the upper end, as seen in fig. 1, will fall at the heel. The edges being thus made to correspond, and the right sides (or outside, when finished,) being faced together, a seam is sewed in the coinciding edges, in the line *m c e*, on each side of the leg, and also from *c f*, thus closing the leg and the bottom of the heel, and bringing the stocking into the shape shown in fig. 2. This sewing is to be performed by means of a single-thread sewing-machine, which is threaded with yarn of the same kind as the web is formed from, be it woollen, cotton, silk, or worsted.

As the usual chain-stitch, formed by a single-thread sewing-machine, constitutes a stitch similar to a common knitting-stitch, one loop being drawn through the previous loop in both cases, the seam formed in sewing the part *A* to the part *B* can hardly be discovered in the completed stocking, when the proper yarn is used in sewing, and being equally elastic and yielding at the line of joining as at any other point, the rigid welt or seam found in some sewed hosiery is avoided.

The stocking thus formed is a close imitation of a hand-knit stocking made in one piece, and is a perfect substitute therefor, in point of durability and comfort, while it can be manufactured of the same quantity of yarn, and at a much less cost.

By the process above described, the labor of making hosiery can be subdivided and apportioned, so as to allow a thorough division of labor, and employ all the machinery to the best advantage, and upon that distinct portion of the work for which it is adjusted.

I am aware that stockings have heretofore been made by cutting portions from a continuous tubular web, and sewing the same together by hand, making certain seams in the feet, between the quarters and the vamp, and also at the back side of the leg, and do not desire to claim stockings so made as of my invention.

Having described my invention, what I claim as new therein, and desire to secure by Letters Patent, is—

As an article of manufacture, a stocking formed substantially as described, and having the side seams *m c e* machine-sewed, substantially as described.

In witness whereof, I have hereunto set my hand, this 12th day of June, A. D. 1868.

ELAM O. POTTER.
